Patented Oct. 3, 1922.

Levi D. Young INVENTOR.

BY

Joseph A. Miller ATTORNEY.

UNITED STATES PATENT OFFICE.

LEWIS D. YOUNG, OF PROVIDENCE, RHODE ISLAND, ASSIGNOR TO YOUNG BROTHERS,
OF PROVIDENCE, RHODE ISLAND, A FIRM.

BOX FASTENER.

Application filed September 26, 1921. Serial No. 503,191.

To all whom it may concern:

Be it known that I, LEWIS D. YOUNG, a citizen of the United States, residing at Providence, in the county of Providence and 5 State of Rhode Island, have invented new and useful Improvements in Box Fasteners, of which the following is a specification.

This invention relates to certain new and useful improvements in box fasteners and 10 more particularly relates to fasteners of the type which are formed of bendable tongues or fingers that are projected through slits provided therefor in the box lid and which are then bent over to lie in superimposed 15 relation to the lid.

The primary object of the invention is to provide improved fingers which are possessed of increased longevity, i. e., which are capable of being bent into and out of lid 20 securing position a large number of times without breaking.

A further object of the invention is to provide means for the aforementioned purpose which also acts to more effectively secure 25 the lid in position and which at the same time can be easily bent and also bent along a fixed line throughout the life of the fingers.

In the drawings:

30 Figure 1, is a longitudinal sectional view of the invention affixed to a box;

Figure 2, is an end elevation, the lid being removed;

Figure 3, is a section on line 3—3 of Figure 2, and

Figure 4, is a detail plan view of one of the fasteners.

In proceeding in accordance with the present invention the fasteners employed are 40 formed of blanks as depicted in Figure 4, wherein the tongues or fingers 1, have base spurs 2 that are clinched to the box or body B, so that the upper or free end portions of the fingers project, as customary, for a distance above the upper edges of the box 45 ends, as illustrated in Figure 2.

The present invention resides in the formation of two spaced transverse rows of punched or struck-out teats or knobs 3, each 50 teat or knob being hollow or of concave-convex cross-section, or otherwise stated, of cup-like form. These two rows of knobs are arranged in reverse order, i. e., the convex sides of the knobs of the lower row face 55 outwardly, while the convex sides of the

knobs of the upper row face inwardly, or downwardly when the fingers are in lid securing position. The space between the two rows of knobs occurs at points alined with the upper edge of the box B and forms a 60 line of hinging or bending on or about which the free ends of the fingers are moved.

These knobs greatly strengthen the fingers or tongues on lines transversely thereof, and in so doing render the parts of the fingers 65 in the space between the knobs relatively weakened so as to readily permit of bending of the fingers. By facing the knobs in opposite directions as shown and above described, the bending is facilitated, since same occurs 70 toward the concave sides of the lower row. In addition, the line of bend is thus positively confined to the space between the two rows of knobs, whereas heretofore the lines of bend have been indeterminate, relatively 75 speaking and widely scattered, resulting in rapid distortion of the fingers and either breakage thereof, or impairment of efficiency and difficult straightening, in an endeavor to remove the numerous kinks 80 resultant from bending along various lines.

In further addition, it will be noted that the knobs of the lower row afford projection which somewhat bite into or frictionally engage against the flange of the top T, while 85 the knobs of the upper row are similarly engaged with the upper face of the top T, so that the latter is more effectively held in place.

Having thus described my invention, what 90 I claim as new and desire to secure by Letters Patent is:

1. In a box fastener, a tongue having means at one end for securing same to a box and having a pair of spaced transverse rows 95 of punched knobs of concavo-convex cross-section disposed intermediate its ends, the convex sides of the knobs of the rows facing in opposite directions and the space between said rows being disposed to aline with the 100 top edge of the box.

2. In a box fastener, a tongue having means at one end for securing same to a box and having a pair of spaced transverse rows of punched knobs disposed intermediate 105 its ends, the space between said rows being disposed to aline with the top edge of the box.

3. In a box fastener, a body, a bendable lid securing tongue attached at one end 110

thereto, and a pair of spaced transverse rows of reinforcements formed in the tongue.

4. In a box fastener, a body, a bendable lid securing tongue attached at one end thereto, and a pair of transverse reinforcing means formed in the tongue, said means being spaced so as to allow bending of the tongue in such space.

5. In a box fastener, a body, bendable lid securing tongues attached thereto, a lid for the body having a flange, and spaced means formed in the tongue and extending out-

wardly therefrom to define a line on which the tongue bends and being arranged so that one of the means engages in the flange and 15 the other engages in and on top of the lid.

In testimony whereof I have signed my name to this specification in the presence of two subscribing witnesses.

LEWIS D. YOUNG.
